Primary Examiner — Katherine A Holbrow*Assistant Examiner* — Riya Salil Kamat(74) *Attorney, Agent, or Firm* — BARNES & THORNBURG LLP; Jeffrey R. Stone(57) **CLAIM**

The ornamental design for an exercise equipment, as shown and described.

DESCRIPTION

FIG. 1 is a perspective view of an exercise equipment showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The dash-dash broken lines show portions of the exercise equipment that form no part of the claimed design.

The dash-dot broken lines show the boundary of the claim and form no part of the claimed design.

1 Claim, 3 Drawing Sheets(56)
